UNITED STATES PATENT OFFICE.

FREDERICK E. ALLEN, OF BOSTON, MASSACHUSETTS, ASSIGNOR TO IMPROVEMENTS MANUFACTURING COMPANY, OF BOSTON, MASSACHUSETTS, A CORPORATION OF MAINE.

WEATHER-STRIP.

SPECIFICATION forming part of Letters Patent No. 695,993, dated March 25, 1902.

Application filed March 26, 1901. Serial No. 52,936. (No model.)

To all whom it may concern:

Be it known that I, FREDERICK E. ALLEN, of Boston, in the county of Suffolk and State of Massachusetts, have invented certain new 5 and useful Improvements in Weather-Strips, of which the following is a specification.

This invention relates to weather-strips for doors in which the strip is pivoted to the door and is adapted to be swung downwardly 10 by the closing movement of the door to make a tight joint with the door-sill or other adjacent surface.

The invention has for its object to provide a simple and effective weather-strip of this 15 character adapted to be put upon the market in a length sufficient for a door of maximum width and to be reduced in length by the party applying it to suit narrower doors, the reduction in length having no effect upon the operativeness of the device.

The invention consists in the improvements which I will now proceed to describe and claim.

On the accompanying drawings, Figure 1 represents a perspective view showing a portion of the swinging edge of the door and a portion of the door-casing and threshold, the door and casing being provided with a weather-strip and an operating device or 25 striker therefor in accordance with my invention, the door being ajar. Fig. 2 represents an edge view of the door in the position shown in Fig. 1. Fig. 3 represents a view similar to Fig. 1, the door being closed. Fig. 30 4 represents an edge view of the door when closed and a sectional view of the threshold. Fig. 5 represents a perspective view of the striker attached to the door casing or jamb. Fig. 6 is a perspective view of the weather-40 strip, with its operating-rod removed from its socket. Fig. 7 represents a perspective view showing the weather-strip rod and socket connected. Fig. 8 represents a view similar to Fig. 4, showing a modification, the weather-45 strip being located at the outer side of the door. Fig. 9 represents a cross-section on line 9 9 of Fig. 7.

The same letters of reference indicate similar parts or features, as the case may be, wherever they occur.

In the drawings and referring for the present to Figs. 1 to 7, inclusive, *a* represents a

weather-strip, which may be made of felt, leather, or other suitable flexible material, and may, if desired, be a strip or ribbon of 55 thin and resilient sheet metal, such as steel.

b represents a rod, to which the strip *a* is attached by means of a sleeve *c*, of thin sheet metal, partially encircling the rod *b* and having flanges *c' c'*, which bear upon opposite 60 sides of the strip *a* and are riveted or otherwise secured thereto, the sleeve *c* being firmly secured to the rod *b* in any suitable way, so that both will rotate together, the rotation of the rod and sleeve swinging the strip *a*, 65 as indicated in Figs. 2 and 4. The rod *b* and the sleeve *c* thereon are journaled in an elongated socket *d*, composed of a strip of sheet metal which is rolled to form a socket portion, which surrounds more than half the 70 diameter of the rod *b* and its sleeve *c*, so that said rod and sleeve can turn in the socket and are confined therein. The strip forming the socket *d* is provided with a flange *d'*, 75 which is formed to bear upon the upper surface of a slot or recess *f*, cut in the bottom of the door *g*, said flange being provided with holes to receive attaching-screws, which secure it to the door.

h represents a spring which is coiled about 80 a portion of the rod *b* and sleeve *c*, one end of the spring being attached to the rod and the other to the socket *d*, the spring being arranged to normally hold the rod, with the strip *a*, in the raised position shown in Figs. 85 1 and 2.

One end of the rod *b* is bent substantially at right angles to the body of the rod and forms an arm *b'*, which projects from the swinging edge of the door *g* and is normally 90 held by the spring *h* in position to engage the inclined outer end of a guide or striker *i*, attached to the jamb or casing *j*, said striker being so arranged that when the door is moving to its closed position the arm *b'* will come 95 in contact with the striker and will be raised thereby from the position shown in Figs. 1 and 2 to that shown in Figs. 3 and 4, the rod *b* being thus turned to swing the strip *a* downward and cause its free edge to bear 100 closely against the door-sill or threshold *k*. A firm and practically air-tight connection is thus afforded between the strip and the threshold. When the door is open, the spring

returns the rod and strip to their normal positions, raising the strip from the threshold.

It will be seen that the described construction enables the strip and its supporting rod 5 and socket to be made of any desired length, so that it can be put upon the market in a length suitable for doors of maximum width and can be reduced in length to any desired extent by cutting off the superfluous parts 10 at the right-hand end, as viewed in Fig. 7, an operation which can be easily accomplished by means of a hack-saw.

The socket *d* and its flange *d'*, extending continuously the entire length of the strip *a*, 15 (excepting where the socket is cut away for the opening *h*), coöperate with the strip in forming an air and dust proof joint under the door, the socket covering practically the entire length of the upper face of the slot *f* 20 in the door, so that there is no objectionable air-admitting crevice above the strip *a*. In practice the spring *h* will practically fill the place of the cut-away portion of the socket, the convolutions of the spring being shown in 25 Fig. 7 more widely separated than they would be in actual use.

The rod *b* and sleeve *c* constitute an elongated journal, to which the strip or flap *a* is attached, and the socket *d* constitutes an 30 elongated journal-bearing, in which said journal is fitted to turn to raise and depress the strip, said bearing having an opening in the lower side through which the strip projects and in which it is adapted to oscillate, the 35 width of the opening being less than the diameter of the journal, so that the journal and strip are supported by the bearing and permitted to oscillate by the opening. The edges *o o* of said opening constitute stops adapted 40 to limit the movements of the strip.

In Fig. 8 I have shown a modification in which the rod *b* and the sleeve *c* are contained in a socket *d²*, which forms a part of a strip which is bent to form a projecting casing *d³*, concealing the rod and strip, and having a vertical flange *d⁴*, adapted for attachment to the inner side of the door. In this case the striker *i* will be elongated, so as to extend farther back from the front of the 50 jamb than in the construction shown in the other figures.

I do not limit myself to the means here shown for operating the strip *a*, and the same may be variously modified without departing 55 from the spirit of my invention.

It is obvious that the journal may be of any other suitable construction and that the strip or flap *a* may be attached to it in any other mechanically equivalent way.

Having thus explained the nature of the invention and described a way of constructing and using the same, although without attempting to set forth all of the forms in which it may be made or all of the modes of its use, 60 I declare that what I claim is—

1. A weather-strip comprising an elongated socket or journal-bearing having a longitudi-

nal opening in its lower side and means for attachment to a door, an elongated journal fitted to turn in said bearing, a strip or flap 70 projecting from the journal and through the said opening, the width of the opening being less than the diameter of the journal, and means for oscillating the journal to raise the lower edge of the strip clear of frictional contact with objects below it. 75

2. A weather-strip comprising an elongated socket or journal-bearing having a longitudinal opening in its lower side, and a flange adapted for attachment to a door, an elongated 80 journal fitted to turn in said bearing, a strip or flap projecting from the journal and through said opening, the width of the opening being less than the diameter of the journal, and means for oscillating the journal to raise the 85 lower edge of the strip clear of frictional contact with objects below it.

3. A weather-strip comprising an elongated socket or journal-bearing having a longitudinal opening and an attaching-flange, an elongated 90 journal fitted to turn in said bearing and a strip or flap projecting from the journal and through said opening, said journal being composed of a rod, and a sleeve placed upon the rod and having flanges between 95 which the strip is held.

4. A weather-strip comprising an elongated socket or journal-bearing having a longitudinal opening on one side, and an attaching-flange, an elongated journal fitted to turn in 100 the bearing, a strip or flap projecting from the journal and through said opening, and a spring engaged with the socket and journal and adapted to normally hold the journal and flap in the raised position of the flap, the journal being provided with a flap-depressing member adapted to coöperate with a complementary fixed member to depress the flap when the door is closed. 105

5. A weather-strip comprising an elongated 110 socket or journal-bearing having a longitudinal opening on one side, and an attaching-flange, a journal fitted to turn in said bearing, a strip or flap projecting from said journal and through said opening, a spring engaged with the socket and journal and adapted to raise the flap, and an arm on one end of 115 said journal adapted to engage a fixed cam or striker to depress the flap when the door is closed.

6. A weather-strip comprising an elongated socket or journal-bearing having a longitudinal opening on one side, and an attaching-flange combined with a cam or striker affixed to the door-casing and formed to move the 125 arm against the force of the spring when the door is being closed.

In testimony whereof I have affixed my signature in presence of two witnesses.

FREDERICK E. ALLEN.
